PULL TAB FOR CONTAINERS OR THE LIKE

John S. Bozek, Chicago, Ill., assignor to Continental Can Company, Inc., New York, N.Y., a corporation of New York

Filed Oct. 23, 1963, Ser. No. 77,119

Term of patent 14 years

(Cl. D58—26)

FIGURE 1 is a top perspective view of a pull tab for containers or the like showing my new design;

The stippled shading is used to indicate contrast in surface texture.

I claim:

The ornamental design for a pull tab for containers or the like, as shown and described.
